ELECTRIC ARC METALLIZING SPRAYER

Dean W. Myers, Newport Beach, Calif., assignor to
Plasmadyne Corporation, Santa Ana, Calif., a corpora-
tion of California

Filed May 22, 1961, Ser. No. 65,264

Term of patent 14 years

(Cl. D62—2)

FIG. 1

FIG. 2

FIG. 3

FIGURE 1 is a front perspective view of an electric arc metallizing sprayer embodying my new design;

FIGURE 2 is a rear perspective view thereof; and

FIGURE 3 is a side elevation of the sprayer.

I claim:

The ornamental design for an electric arc metallizing sprayer, substantially as shown.
